LAPEL BUTTON

Jay C. Morris, Alexandria, Va., assignor to the United States of America as represented by the Secretary of the Army

Filed Sept. 27, 1962, Ser. No. 71,950

Term of patent 14 years

(Cl. D29—2)

Fig. 1.

Fig. 2.

Fig. 3.

(Granted under Title 35, U.S. Code (1952), sec. 266)
FIGURE 1 is a front elevational view of a lapel button showing my new design;

FIGURE 2 is a side elevational view thereof; and
FIGURE 3 is a top plan view of the same.

The essential features of my design reside in the full line showings on the drawing.

The invention described herein, if patented, may be manufactured and used by or for the Government for governmental purposes without the payment to me of any royalty thereon.

I claim:

The ornamental design for a lapel button, substantially as shown and described.
